ASSIGNORS TO E. PAYSON SMITH, OF SPRINGFIELD, ILLINOIS.

BRAKE-HANGER SUPPORT

Application filed July 14, 1926. Serial No. 122,302.

Our invention relates to means for supporting the hangers for the brakes of railroad cars in such manner that the hangers or links are pendently supported in place on 5 the truck side frames.

Brake hangers are usually supported from an integral portion of the truck side frame which in our construction consists of projections or lugs cast integral with the steel side 10 frame. These portions or lugs project from the side frame a sufficient distance and in a direction transversely of the wheels of the truck; while the hangers or suspending elements are usually in the nature of U-shaped 15 links as illustrated in the drawing or they may be of the loop or continuous link type.

Our invention contemplates a construction which will permit the use of either types 20 of links or hangers so that the substitution of the one for the other may be readily made without alteration or change in the projecting portions or lugs on the side frame or in the keeper or retainer element employed.

Our invention contemplates means where- 25 by a three point upward thrust receiving element or member is provided which at the same time acts as a keeper or retainer for the hanger or suspending element and which is of such construction that it may be inserted 30 into place after the hangers or supporting means have been properly placed on the projections or lugs of the side frame and which therefore may be independently removed 35 when occasion requires. Our construction therefore permits assembly of the parts and suspension of the brake to be readily accomplished.

The objects and advantages of our invention 40 will be readily apparent from the detailed description of the accompanying drawing, wherein—

Figure 1 is an elevation of a portion of a truck side frame and portions of the suspending hanger or link with our improved retainer element or keeper means shown applied.

Figure 2 is a perspective view of a portion 45 of the truck side frame and with its projecting portions or lugs, with parts broken away to show internal construction; the sus-

pending link and retainer element or keeper being removed.

Figure 3 is a perspective view of the keeper or retaining element looking at the bottom side thereof.

In the particular exemplification of the invention as disclosed in the drawing, a portion of the truck side frame is shown at 10 provided with the projection 11 formed integral with the truck side frame and reenforced by the web portion 12. The projection 11 is disposed in a transverse direction relative to the truck side frame and the wheels and the projection is slotted longitudinally to provide the top and bottom portions or bifurcations 13 and 14 on the wheel side thereof. The bifurcations or portions 13 and 14 at an intermediate point are each shown provided with a corresponding lip 15 arranged parallel in vertical spaced relation as more clearly shown in Figure 2 and each lip apertured at 16 to receive a headed pin 17 which is inserted after the brake hanger and the keeper element have been put into place.

The lower portion or bifurcation 14 of the projection 11 is longitudinally grooved as shown at 18 in Figure 2 to receive the usual supporting pin shown in dotted lines in Figure 1 at 19 when the hanger is of the U-shape shown at 20 in Figure 1; or to receive one end 80 of the hanger if the latter is of the loop or continuous type frequently employed in this art.

The lower bifurcation is also slotted transversely as shown at 21, 21 at suitable spaced points apart to receive the legs or sides of the hangers in order that the hanger may straddle the intermediate portion of the lower bifurcation 14 and permit free oscillatory 85 movement of the hanger.

In order to accommodate the construction to the U-shaped hanger which has enlarged eyeleted ends, the upper bifurcation 13, at points coincident with the transverse slots 21, 21, is transversely grooved as shown at 22, 22.

The projection 11 in what may be termed the rear wall thereof and at a point coincident with the intermediate portion of the lower bifurcation 14 is provided with a pocket 23 having a shoulder or ledge 24 for the 100

purpose of receiving the lip or projection 25 of the keeper or retainer element 26 shown in Figure 3.

The keeper or retainer element 26 is of a thickness corresponding substantially with the vertical spacing between the bifurcations 13 and 14 in order that the keeper or retainer element may freely slide into place after the hanger or its supporting pin, as the case may be, has been inserted into position in the groove 18. The keeper or retainer element 26 comprises a metallic plate which is slotted transversely as shown at 27, 27 at points adapted to correspond with the transverse slots 21, 21, in order to fit over and around the upper ends of the hangers, whether of the U-shape or loop type, and permit free oscillatory movement thereof.

The keeper or retainer element as stated is adapted to fit over the pivotally supported upper end of the hanger and for that reason the keeper or retainer plate along the inner longitudinal side is dished on its lower face as shown at 28 to accommodate it to the retaining pin 19 or to the upper end of the loop hanger. The dishing 28 extends lengthwise of the keeper plate or retainer element 26 beyond the transverse slots 27, 27, terminating a slight distance short of the ends of the keeper plate or retainer element so as to leave the depending lips or projections 29, 29 at both ends. These lips 29 are adapted to extend across the ends of the supporting rod or headless pin 19 and thus prevent longitudinal movement of the latter. As is apparent, these depending lips 29, 29 will hold the supporting pin 19 against longitudinal movement and thus obviates the necessity of providing any additional means for locking the pin in place. It will be understood that the retainer element or keeper plate 26 is therefore of length slightly greater than the length of the lower projection 14 so that the depending lips 29, 29 will be disposed slightly beyond the sides of the two outer portions or ends of the lower bifurcation 14.

The keeper plate or retainer element 26 at what may be termed its outer side is shown apertured at 30 which is adapted to register with the apertures 16 in the upper and lower bifurcations 13 and 14 to receive the retaining pin 17. The projection or lip 25 of the keeper plate or element 26, as previously stated, enters the socket or pocket 23 in the rear wall of the projection 11 and rests on the shoulder or ledge 24 and acts as a centering element which also prevents lateral oscillatory movement of the keeper plate or element 26.

With our improved structure the keeper plate or element, especially when employed in connection with the U-type hanger, provides a three point surface adapted to receive the upward thrust of the hanger or its suspend-

ing pin and thus relieves the upper bifurcation 13 of the integral side frame projection 11 of all wear.

In the application of the brakes, one set of brakes, namely the set on the side of the wheels toward which they are turning, causes a downward pull on the hanger, while the other set of brakes, namely the set of brakes on the rear side relative to the direction in which the wheels are turning, causes an upward thrust on the hanger during each application of the brakes. It has been found in practice that this constant upward thrust causes considerable wear on the supporting lugs or projections of the side frames, inducing a considerable amount of chatter in the supporting elements, especially after a slight wear has been encountered. This soon results in an increase in wear and undue play to such an extent that proper application of the brakes is affected. As this wear, without our keeper plate, is on an integral part of the side frame where it cannot be renewed or repaired, it soon necessitates discarding the side frames of the truck before their usefulness otherwise is impaired, thus entailing considerable loss in time and expense.

The exemplification of the invention as disclosed in the drawing is believed to be the best embodiment of the invention, the description whereof is made in terms employed merely to describe the structure which may be modified in certain respects without, however, departing from the spirit of our invention.

What we claim is:

1. In a brake hanger support, a truck side frame provided with a projection slotted longitudinally to provide vertically spaced bifurcations with the lower bifurcation slotted transversely and grooved longitudinally, a keeper plate adapted to fit intermediate of the bifurcations and having its lower face dished at a point coincident with the longitudinal groove in the lower bifurcation.

2. In combination with a truck side frame provided with a bifurcated extension disposed in a transverse direction, the lower bifurcation being grooved longitudinally and slotted transversely at horizontally spaced points, with said slots extending beyond and intersecting said groove, a keeper plate insertible between said bifurcations and extending throughout the length of the lower bifurcation, the lower face at the inner end of said plate being dished, and means for removably securing the keeper plate in place.

3. In a brake hanger support, a keeper plate for holding the hanger in place comprising a plate dished on its lower side adjacent to the inner longitudinal edge, with the dishing terminating short of the ends of the plate to provide end walls at opposite ends of the dished portion.

4. In a brake hanger support, a keeper

plate for holding the hanger in place comprising a plate dished on its lower surface lengthwise of one of its longitudinal edges with the dishing terminating short of the ends of the plate to provide abutting shoulders at opposite ends, the plate being slotted transversely of the dished portion.

5. In combination with a truck side frame having a longitudinally slotted projection and a pair of slots in the projection disposed transversely of the longitudinal slot and provided with a socket at the inner side of the longitudinal slot, intermediate of the transverse slots, a keeper plate adapted to fit into said longitudinal slot, the inner longitudinal side of the plate being dished on its lower face, said plate being slotted transversely at points adapted to register with the transverse slots in the side frame, a projection on the keeper plate adapted to fit into said socket.

6. The combination with a brake hanger and a truck side frame slotted longitudinally to provide upper and lower bifurcations, the lower bifurcation being grooved longitudinally to receive a brake-hanger or hanger pin, the lower bifurcation being transversely slotted for passage of the sides of the hanger, both bifurcations being provided with registering apertures, of a keeper plate adapted to fit between the bifurcations, said plate being transversely slotted at points registering with the transverse slots in the lower bifurcation, the lower face of the plate at its inner longitudinally side being dished, the ends of the plate being formed to depend across the ends of the grooves in the lower bifurcation, while the outer longitudinal side of the plate is apertured at a point registering with the apertures in the bifurcations.

7. In combination with a truck side frame provided with projections arranged parallel in vertically spaced relation, the lower projection being longitudinally grooved and transversely slotted, a keeper plate adapted to fit between said projections and to extend beyond the transverse slots of the lower projection, the lower face of the plate being dished at a point corresponding with the groove in the lower projection, the ends of the plate being disposed across the ends of the groove in the lower projection, and means for removably securing the plate between said projections.

8. In combination with a truck frame provided with vertically spaced projections formed to provide a longitudinal groove therebetween, a keeper plate insertible between said projections and having a dished face, said dishing terminating short of the ends of the plate to provide abutting shoulders at opposite ends, and means whereby the plate is removably secured between said projections.

9. In combination with a truck frame provided with a laterally extending arm slotted

longitudinally from one side intermediate of the top and bottom of the arm so as to provide vertically spaced portions on one side of the arm, the lower portion on its upper surface and removed from the outer longitudinal edge being grooved, both of said portions being formed to provide lips having registering openings therethrough, a keeper plate insertible between said vertically spaced portions and having a dished face, the outer longitudinal side of the plate having an apertured portion adapted to register with the openings in said lips, and means adapted to pass through the registering openings in said lips and in said plate whereby the plate is movably secured in place.
